WINDING MACHINE

William T. Stearn and Frank W. Schulte, Cumberland, Md., assignors to Celanese Corporation of America, a corporation of Delaware

Application February 9, 1944, Serial No. 521,631

6 Claims.

(Cl. 242—18)

This invention relates to yarn winding machines, and relates more particularly to a pressure stabilizer for winding machines on which cones and like packages of yarn are wound.

In textile machines for winding yarn into cones and like packages wherein the yarn is traversed longitudinally of the yarn package by a reciprocating yarn guide, the yarn guide is mounted on a traverse frame assembly and bears against the surface of the yarn package during the winding operation. The traverse frame assembly which carries the yarn guide comprises a pivoted arrangement whereby the yarn guide in contact with the surface of the yarn package is permitted to move progressively as the diameter of the yarn package increases. This movement of the traverse frame assembly is derived from the pressure of the yarn guide against the surface of the yarn package, the yarn guide being maintained in contact with the yarn package with a suitable counterweight mounted at the base of the pivoted traverse frame supporting arm. In prior winding machines of this type, difficulties were encountered in applying the necessary or proper amount of yarn guide pressure with the result that the yarn package winding pressure and the yarn package density control have not been what is desired.

It is, therefore, an important object of our invention to provide a simple and efficient means for attachment to the winding mechanism provided with a traverse frame back whereby the motion of said traverse frame back and the yarn guide pressure on the yarn package being wound may be controlled in a positive manner, i. e. stabilized.

Other objects of this invention, together with certain details of construction and combination of parts, will appear from the following detailed description and drawing.

Our invention will now be described in greater detail, particularly with reference to the accompanying drawing, wherein a preferred embodiment of our invention is shown. It is to be understood, however, that this description is given by way of example only and is in no way limitative.

In the drawing, the figure is an end elevational view showing a yarn winding mechanism of the usual type with our novel pressure stabilizing attachment applied thereto.

Referring now to the drawing, the reference numeral 1 indicates generally a winding machine of the conventional type, for example, of the type manufactured by the Universal Wind-

ing Machine Company. A plurality of such winding units are normally positioned on a single support or frame. The winding machine comprises a spindle 2 driven by suitable means, 5 which is not shown in the drawing since it is not necessary to an adequate understanding of the present invention, a traverse frame assembly generally indicated by reference numeral 3, a cam box 4, a yarn tension device 5, stopping wheel 6 normally used in combination with a stopping lever for halting the operation of the winding machine. The traverse frame assembly 3 comprises a reciprocating traverse bar 7 carrying a yarn guide 8 which rests against and is supported by a plate 9. The traverse bar 7 is adapted to move in a supporting member 11, and the traverse frame is provided with the usual counterweight 12.

The description and functioning of our novel attachment for stabilizing the pressure on the yarn package 13 will now be described. The yarn 14 is drawn from any suitable source of supply (not shown) through the gate tension device 5 over the thread guide 8 and is wound on to the package 13. During the process of building the package, the counterweight 12 on the traverse frame maintains the guide 8 in contact with the surface of package 13. In accordance with our invention, the movement of the traverse frame through its arc is controlled by the action of the pressure stabilizer which comprises a wire hook 15, one end of which 16 is fastened to the back of yarn guide plate 9 and the other end to a cord 17. The cord passes over a grooved hardwood snubbing block 18 which is fixed by means of a screw 19 to the face plate of cam box 4 of an adjacent winding unit. The cord is also attached to one end of a wire hook 21, the other end of which is fastened to a screw 22 adjustably mounted in a bracket 23 fastened to the counterweight 12. The cord and hook arrangement is held in tension by means of a coil spring 24 attached to the face plate of cam box 4 and hooked to one end of wire hook 21.

Means are provided for controlling the tension of the yarn placed thereon by gate tension device 5. This control of the gate tension is effected through links 25 and 26 connecting the movable gate of the tension device 5 to the counterweight 12, which counterweight is provided with means 27 for holding one end of link 26 in adjusted position. The links are interconnected by means of levers 28 and 29 which are fixed at their inner ends to a pin 31. The initial tension on the yarn 14 is obtained by adjusting the

counterweights 32 and 33 which are carried on graduated beams 34 and 35, respectively. Beam 34 is attached to the free end of lever 29 while beam 35 is fixed to pin 31.

As the traverse frame moves outward with the building up of the package, tension on the yarn and pressure on the yarn package are reduced in order to compensate for increased yarn take-up speed. The tension on the yarn is reduced progressively as the movement of the counterbalance 12 draws open the gate of the tension device through links 25 and 26 which are connected by lever 28. The reduction of the pressure on the yarn package is affected by means of coil spring 24 acting through the medium of cord 17 and connecting wire hooks 15 and 21.

On the standard arrangement of traverse frame dog mechanism, the traverse frame is controlled in an outward direction only in the winding of the package and excessive pressure against the yarn package results if the dogging mechanism is not maintained in perfect adjustment. In using the pressure stabilizer of our invention, clutch or dogging action is dispensed with and the traverse frame is not subjected to the somewhat erratic behavior of the dog and segment. In other words, the predetermined pressure is held throughout the entire operation of yarn package building. This is also reflected in less gate tension vibration which means a more uniform running tension and reduction in yarn package density.

It is to be understood that the foregoing detailed description is given merely by way of illustration and that many variations may be made therein without departing from the spirit of our invention.

Having described our invention, what we desire to secure by Letters Patent is:

1. In a winding machine, the combination with a take-up means for winding yarn into packages, of a yarn guide for traversing the yarn on to the package, a traverse frame assembly, including a yarn guide plate and counterweight, in which said yarn guide is reciprocated, and means for reducing the pressure of said yarn guide on the yarn package during the building up of the yarn package, said means comprising an elastic connection between said yarn guide plate and said counterweight.

2. In a winding machine, the combination with a take-up means for winding yarn into packages, of a yarn guide for traversing the yarn on to the package, a traverse frame assembly, including a yarn guide plate and counterweight, in which said yarn guide is reciprocated, and means for reducing the pressure of said yarn guide on the yarn package during the building up of the yarn package, said means comprising a spring-loaded connection between said yarn guide plate and said counterweight.

3. In a winding machine, the combination with a take-up means for winding yarn into packages, of a yarn guide for traversing the yarn on to the package, a traverse frame assembly, including a yarn guide plate and counterweight, in which said yarn guide is reciprocated, and means for reducing the pressure of said yarn guide on the yarn package during the building up of the yarn package, said means comprising a spring-loaded rope connected to said yarn guide plate and counterweight and means for snubbing said rope.

4. In a winding machine, the combination with a take-up means for winding yarn into packages, of a yarn guide for traversing the yarn on to the package, a traverse frame assembly, including a yarn guide plate and counterweight, in which said yarn guide is reciprocated, and means for reducing the pressure of said yarn guide on the yarn package during the building up of the yarn package, said means comprising a spring-loaded rope connected to said yarn guide plate and counterweight and a snubbing block spaced from said traverse frame assembly for engaging said rope.

5. In a winding machine, the combination with a take-up means for winding yarn into packages and a tension device for applying a tension on the yarn being wound, of a yarn guide for traversing the yarn on to the package, a traverse frame assembly, including a yarn guide plate and counterweight, in which said yarn guide is reciprocated, means for reducing the pressure of said yarn guide on the yarn package during the building up of the yarn package, said means comprising an elastic connection between said yarn guide plate and said counterweight, and a connection between said tension device and said counterweight for reducing the tension of said yarn as the pressure on the yarn package is reduced.

6. In a winding machine, the combination with a take-up means for winding yarn into packages and a tension device for applying a tension on the yarn being wound, of a yarn guide for traversing the yarn on to the package, a traverse frame assembly, including a yarn guide plate and counterweight, in which said yarn guide is reciprocated, means for reducing the pressure of said yarn guide on the yarn package during the building up of the yarn package, said means comprising a spring-loaded rope connected to said yarn guide plate and counterweight, a snubbing block spaced from said traverse frame assembly for engaging said rope, and a connection between said tension device and said counterweight for reducing the tension of said yarn as the pressure on the yarn package is reduced.
